UNITED STATES PATENT OFFICE

ROBERT T. ROMINE, OF MOUNT CLEMENS, MICHIGAN

PORTABLE STACK LIFTER

Application filed August 1, 1927. Serial No. 209,932.

This invention relates to a portable stack lifter or crane particularly adapted to be carried into or out of a freight car for the purpose of lifting heavy loads from the car 5 floor onto a truck platform or other conveying medium, or vice versa.

An object of the invention is to provide a stack lifter of the foregoing character capable of being adjusted vertically to adapt it 10 for use in the handling of relatively high unitary packs of sheet metal, and wherein such adjustment is effected by varying the distance between the lower ends of the supporting legs of the stack lifter and the 15 ground.

Other objects of this invention will appear in the following description and appended claims, reference being had to the accompanying drawings forming a part of this 20 specification wherein like reference characters designate corresponding parts in the several views.

In said drawings:

Fig. 1 is a side elevation of the stack lifter 25 or crane embodying my invention with the parts in their relative normal positions.

Fig. 2 is an end elevation of the construction shown in Fig. 1.

Fig. 3 is a view similar to Fig. 1 showing 30 the stack lifter in its elevated or adjusted position.

Fig. 4 is an end elevation of the stack lifter of Fig. 3.

Fig. 5 is a section taken along the line 35 5-5 of Fig. 3.

Before explaining in detail the present invention, and the method or mode of operation embodied therein, it is to be understood that the invention is not limited in its application 40 to the details of construction and arrangement of parts illustrated in the accompanying drawings, since the invention is capable of other embodiments and of being practised or carried out in various ways. Also it is to 45 be understood that the phraseology or terminology employed herein is for the purpose of description and not of limitation, and it is not intended to limit the invention beyond the terms of the several claims hereto appended 50 or the requirements of the prior art.

This application is a continuation in part of my application Serial No. 104,910, filed April 27, 1926, and my application Serial No. 133,374, filed September 3, 1926.

The portable stack lifter or crane embodying my invention is shown as a whole at V and comprises a substantially arch-shaped frame having four spaced side supports or legs, such as a pair of front legs A and a similar pair of rear legs A¹. Each leg or support is preferably identical in construction, comprising a pair of front and rear parallel structural steel angle bars 10 and 11 respectively. Each pair of angle bars 10 and 11 of each leg is united at the lower end thereof by means of a load distributing foot plate 12 which is riveted to the leg members.

The top frame of the stack lifter comprises a pair of end transverse angle bars 13 and a pair of longitudinal side angles 14. To provide an intermediate floor or supporting frame located below the top frame, transverse channel bars 15 at the front and rear ends of the stack lifter, and longitudinal channels 16 at opposite sides of the frame work, are provided.

The vertical leg members 10 and 11 and the members 13, 14, 15 and 16 are rigidly connected together by means of gusset plates 17 and 18 provided at opposite sides and ends, respectively, at the top of the frame work of the stack lifter.

Housed within the frame work at the upper end is the hoisting mechanism, including reduction gearing, lifting drums and an electric motor, all of these last-mentioned parts being shown and described in my co-pending application Serial No. 133,374, filed September 3, 1926.

The stack lifter is provided with a pair of lifting bars or members B which support at opposite ends sheaves or pulley wheels C. Cables D pass about the sheaves C and are adapted to be wound upon the winding drums E. In order to lift and lower the bars C, the electric motor M is operated and serves to wind or release the cables D through the medium of the hoisting mechanism above referred to. A control lever F is provided for the purpose of supplying or cutting off the electric current for operating the motor. Each of the legs A and A¹, and preferably the

100

angle 11 of each leg, is provided with a lifting dog G.

Adjacent their lower ends, the angles 10 and 11 of each leg are provided with a series of holes or apertures 10^a and 11^a.

For the purpose of supporting the stack lifter when not under load to permit it to be propelled or wheeled about, the following construction is provided. At each side of the frame is mounted a horizontal slide member 19 which serves to interconnect each forward and rear pair of legs A and A¹. As shown in Fig. 5, this member 19 is in the form of a continuous rectangular sleeve which embraces each leg support A and A¹ and is slidable vertically relatively thereto. At the forward end of the stack lifter the member 19 projects beyond the angle 10 and supports a bracket 20 which carries a spring mounted 20 caster wheel 21. The member 19 adjacent the angle bar 11 of the leg A¹ is provided with a bracket 22 which serves to support a spring mounted caster wheel 23. The wheels 21 and 23 maintain the lower ends of the legs A and A¹, that is the foot plates 12 carried by these legs, normally out of contact with the ground as shown in the drawings. When a load is hoisted by the crane the springs will be compressed to permit the load to be sustained by 30 the leg supports.

The members 19 at opposite longitudinal sides of the stack lifter are provided with holes or apertures which are adapted to register with the holes 10^a and 11^a. Each member 35 19 is provided with a removable locking pin or the like 24, there being one of these pins provided for each of the apertures. When the pins are in place as shown in the drawings the members 19 are maintained in fixed relation against sliding movement with respect to the legs A and A¹.

In Figs. 1 and 2 the stack lifter is shown in its normal position and at its normal height. When it becomes desirable, however, to increase the height of the stack lifter to that in which it is shown in Figs. 3 and 4, an industrial truck T provided with a load elevating or lift platform L is propelled into position between the pairs of spaced legs as shown 45 in Fig. 2. The lifting dogs G are then swung or moved into position to engage the top of the lift platform L, the pins 24 removed and the platform L raised or elevated to elevate the frame together with the legs A and A¹.

55 relatively to the members 19 as shown in Figs. 3 and 4. The pins 24 are then replaced, this time in the lowermost set of apertures 10^a and 11^a. Blocks H (Figs. 3 and 4) are then inserted beneath the foot plates 12, the lift 60 platform L lowered and the truck backed out from its position between the stack lifter supporting legs. When the load, such as a pack of metal sheets, is elevated by the hoisting mechanism the springs of the caster structures 65 will be compressed causing the lower ends 12

of the legs to rest upon the blocks H. After such a load has been lifted or conveyed from the car the stack lifter may be wheeled to other positions within the car to handle additional bundles or packs. It will be noted that the adjustment of the wheels 21 and 23 enables the lifter to be wheeled off the blocks H. 70

Thus it will be seen that the distance between the lower ends of the legs A and A¹ and the ground may be varied, thereby increasing the height of the stack lifter. It will also be noted that the slideable members 19 carry the spring supported caster wheels 21 and 23 so that, regardless of the height of the stack lifter, the lower ends of its 80 supporting legs are normally maintained out of contact with the floor or the blocks H so that it may be moved about from place to place manually.

When it is desired to return the stack lifter 85 to its normal height or the position in which it is shown in Figs. 1 and 2, the reverse of the lifting operation is performed.

By providing the stack lifter with means for varying or adjusting its height, it is 90 possible to move it through the doorway of a box car and then raise it when in position within the car so that it is capable of handling relatively larger loads. The stack lifter is constructed to enable it to lift and lower 95 average size loads without the necessity of adjustment, but frequently loads of greater dimensions have to be lifted.

What I claim is:

1. A portable stack lifter comprising an 100 arched frame having pairs of legs spaced to permit the introduction of a lift truck platform therebetween, hoisting mechanism carried at the top of the stack lifter, and a slide member provided with spring mounted 105 caster wheels carried by each pair of legs and adjustable vertically relatively thereto for varying the distance between the lower ends of the legs and the ground.

2. A portable stack lifter comprising an 110 arched frame having pairs of legs spaced to permit the introduction of a lift truck platform therebetween, hoisting mechanism carried at the top of the stack lifter, pairs of spring mounted caster wheels, supports for 115 said wheels, and means carried by said legs and slideable thereon for bodily adjusting said supports vertically.

3. A portable crane comprising an arched 120 frame having pairs of legs spaced to provide a crane bay, spring mounted caster wheels carried by the legs, means for vertically adjusting said caster wheels relatively to the legs, and means carried by the legs and adapted to cooperate with a lifting device for enabling the latter to lift the arched frame and 125 permit adjustment of said wheels.

4. In a portable crane, an arched frame having spaced pairs of legs, a bar connecting a pair of legs and slideable vertically there- 130

on, and a pair of wheel carrying supports carried by said bar.

5. In a portable crane, an arched frame having spaced pairs of legs, a bar connecting a pair of legs and slidably vertically thereon, a pair of wheel carrying supports carried by said bar in the longitudinal plane of a pair of said legs, and spring means for permitting said wheels to yield under load.

10. In a portable crane, an arched frame having at each side a longitudinally spaced pair of legs, a bar spanning each pair of legs and slidably mounted thereon, and caster wheel carrying supports carried by said bars.

15. In a portable crane, an arched frame having at each side a longitudinally spaced pair of legs, a bar spanning each pair of legs and slidably mounted thereon, means for connecting each bar to the legs in a plurality of 20 vertically adjusted positions, and caster wheel carrying supports carried by said bars.

25. In a portable crane, an arched frame having at each side a longitudinally spaced pair of legs, a bar spanning each pair of legs and slidably mounted thereon, and swiveled 30 caster wheel carrying supports carried by said bars, each support lying in the longitudinal plane of a pair of the legs.

35. A portable crane comprising an arched frame having pairs of legs spaced transversely to permit the introduction of a lift truck platform, a longitudinal frame bar connecting a pair of legs and adjustable vertically thereon, caster wheels carried by said bars, and means carried by the legs and cooperating with the truck platform for enabling the latter to lift the arched frame and permit vertical adjustment of said bars together with the caster wheels.

40. 10. A portable crane comprising an arched frame having pairs of legs spaced transversely to permit the introduction of a lift truck platform, slide members carried by the legs, spring controlled caster wheel carrying supports fixed to said members, means 45 for adjustably connecting said slide members to the legs, and means carried by the legs and cooperating with the truck platform for enabling the latter to lift the arched frame and permit vertical adjustment of said slide members.

50. 11. In a portable stack lifter or crane, an arched frame having spaced pairs of legs, hoist mechanism carried at the top of said frame, a slide member embracing a leg and slidably vertically thereon, means for detachably securing said member in adjusted position, and a caster wheel structure carried by said slide member and lying in the longitudinal plane of the leg.

55. 12. In a portable stack lifter, an arched frame adapted to carry hoist mechanism at the upper part thereof and comprising spaced pairs of legs, a horizontal frame bar connecting each pair of legs, a pair of caster

wheels positioned in advance of the legs of each pair and disposed in the plane thereof, a device for supporting a caster wheel of each pair from a frame bar, and spring means for causing relative yielding movement of the frame and wheels under load.

60. 13. In a portable crane having hoisting mechanism, the combination of an arched framework having at opposite sides vertical pairs of legs spaced to permit the introduction of a lift truck platform therebetween, the legs of each pair being spaced longitudinally, a side bar connecting said legs, a caster wheel mounted beneath the bar, and spring means cooperating with the bar and caster wheel.

In testimony whereof I affix my signature.
